Attorney

UNITED STATES PATENT OFFICE.

EUGENE M. LE LAURIN, OF SAN ANTONIO, TEXAS.

COLLAPSIBLE FOOT-REST.

1,287,360.

Specification of Letters Patent. Patented Dec. 10, 1918.

Application filed August 14, 1918. Serial No. 249,786.

To all whom it may concern:

Be it known that I, EUGENE M. LE LAURIN, a citizen of the United States, residing at 350 East Commerce street, San Antonio, in 5 the county of Bexar and State of Texas, have invented certain new and useful Improvements in Collapsible Foot-Rests, of which the following is a specification.

This invention relates to collapsible foot 10 rests for shoe shining stands. With shoe stands in which the foot rests are fixed it has frequently happened that persons stepping from the stand have been tripped and thrown by the foot rests and in other cases 15 have had their clothing caught and badly torn by these foot rests.

It is therefore the object of the present 20 invention to provide a collapsible foot rest of simple and economical construction and one which with a single movement, may be lowered to a position where it will not interfere with the movement of a person stepping upon or leaving the stand.

Further objects and advantages of the 25 invention will be set forth in the detailed description which now follows.

In the accompanying drawing,

Figure 1, is a side elevation of a foot rest 30 constructed in accordance with the invention,

Fig. 2, is a vertical sectional view illustrating the foot rest in collapsed position, and

Fig. 3, is a plan view of the supporting 35 sleeve of the foot rest with the foot rest stem in section.

Like numerals designate corresponding parts in all of the figures of the drawing.

Referring to the drawing 5, designates 40 the platform of a shoe shining stand. It is to be understood that there may be as many of the foot rests shown, as is found to be desirable. Each foot rest comprises a foot support 6, and a stem 7, these stems being 45 slidably disposed in sleeves 8 which are attached to the platform 5, through the medium of collars or flanges 9 and screws 10. Each sleeve has a slot 11, extending entirely therethrough through which a stud 12 carried by the stem 7 is adapted to pass when the foot rest is turned to such a position that this stud alines with the slot. Each flange 50 or collar 9 is provided opposite its slot 11 with a concave seat or pocket 13 within

which the stud 12 rests when the foot rest is 55 in elevated position. This structure prevents accidental turning of the foot rest 6 and holds it in proper alignment.

It will be readily understood that by turning the stud 12 until it alines with the slot 60 11 said stud may pass through the slot and the foot rest may be brought to a position illustrated in Fig. 2.

While the elements herein shown and described are well adapted to serve the purposes for which they are intended it is to be understood that the invention is not limited to the precise construction set forth but that it includes within its purview whatever changes fairly come within the spirit 70 of the appended claims.

Having described my invention what I claim is,

1. In a device of the character described the combination with a foot support and its 75 stem, of a slotted element through which said stem slides and a lateral extension carried by said stem adapted to pass through the slot of the element when alined therewith or to rest upon the element to hold the 80 foot support in an elevated position when out of alignment with said slot.

2. In a device of a character described the combination with a foot support and its 85 stem, of a sleeve through which said stem slides, a stud projecting laterally from said stem, said sleeve having a slot through which the stud is adapted to pass and a seat formed in conjunction with said sleeve in which said stud is adapted to rest.

3. The combination with a shoe shining stand, of a member carried thereby comprising a sleeve and a flanged collar the latter resting upon the stand and the sleeve projecting through the stand, a foot support, a stem by which the foot support is carried, said stem being slidably disposed in the sleeve, a laterally projecting stud carried by the stem, said sleeve being longitudinally slotted for the passage of said stud 95 and said collar having a concave seat formed therein for the reception of the stud, whereby the stem and foot support are held in elevated position and are held against turning with relation to the sleeve.

In testimony whereof I affix my signature.

EUGENE M. LE LAURIN.
